CARD OPERATED ROTARY CONTACT

Fritz A. Deutsch, East Orange, N. J., assignor to Monroe Calculating Machine Company, Orange, N. J., a corporation of Delaware

Application October 2, 1956, Serial No. 613,519

8 Claims. (Cl. 235—61.11)

This invention relates to devices for sensing perforated designations in a record card or the like and more particularly to card operated rotary contact devices which are adapted for effecting a series of electrical impulses upon the sensing of a selective series of such designations while the record cards are in motion through the usual card feeding mechanism associated with accounting and statistical machines.

The invention contemplates improvement in card sensing devices of the type such as for instance disclosed in U. S. Patent 2,517,984 issued August 8, 1950 to James M. Cunningham wherein a sensing element in the form of a star wheel is rotatably mounted on the end of a lever and rests upon a record card to traverse a perforated column thereof. In the devices of the patent two points of the star wheel rest on the card surface and as a hole arrives and passes beneath the near point said point will roll into the hole, allowing the center of the wheel to drop thereby rocking the supporting lever. Upon such operation a suitable plunger means provided between said lever and a resilient contact arm is caused to be operated for engaging the contact arm with a related fixed contact member and effect thereby an electrical circuit. It will be noted however that such engagement is made without benefit of any wiping action at the contact point.

In such earlier known devices, where the holes sensed follow one another in close proximity, as where they are spaced a distance equal to the pitch of the teeth or points of the above star wheel, the wheel will shift bodily upon sensing the first hole and will thereafter simply roll from one hole to the next without shifting the center of the wheel and the contacts will thus remain in engaged condition to maintain the circuit for as long as the succession of closely spaced holes continues. Under such condition for effecting a pulse circuit in accordance with each of the said perforations auxiliary pulsing devices have been provided heretofore which devices are operable in timed relation with the record card in known manner.

A principal object of the present invention is to provide an improved and compact rotary card sensing device having a gear wheel the teeth of which are adapted for engaging an intermittent series of perforations in a record card for rotation thereby and which teeth serve also as a plurality of electrical contact elements adapted to be brought successively thereby into circuit engagement with a fixed electrical contact member so as to effect a selective series of electrical impulses.

As a further object the invention provides for a rotary card sensing gear wheel the teeth of which form a series of contact elements in common and adapted for successive engagement with a common fixed contact bar to effect thereby a series of electrical impulses in accordance with a series of card perforations, without utilizing auxiliary pulsing means such as heretofore known to the art.

Another object of the invention is to provide sensing gears rotatable by the record card and which leave a series of angularly spaced electrical contact areas thereon each

2

adapted for effecting a wiping action with a fixed contact member to assure electrical circuit therewith.

As a further object the invention provides for a card operated rotary contact device employing fewer parts than the heretofore known art in that a series of electrical control circuits are now effected directly through the rotary sensing wheel.

Other objects and structural details of the invention will be apparent from the following description when read in connection with the accompanying drawing wherein:

Fig. 1 is a side elevation of the device and showing means for advancing the record card.

Fig. 2 is an enlarged detail elevation of the card sensing rotary contact gear wheel, shown in normal position just prior to operation thereof by a record card.

Fig. 3 is a similar view with a pair of teeth of a contact gear wheel riding on an imperforate portion of a record card.

Fig. 4 is a similar detail view, with the contact wheel at mid-operated position in engagement with the fixed contact member, the wheel being traversed by a series of closely spaced perforations.

Referring to the drawings, the record card feeding mechanism is diagrammatically represented by pairs of feeding rollers 10 which advance a record card 11 toward the right with a continuous movement across a supporting plate 12. The card 11 is of well-known type, such as the I. B. M. record card, having perforations 13 arranged in the usual columns and rows according to the data their location represents.

In line for sensing each of the columns of the perforations 13 is a related contact member in the form of a six tooth gear wheel 14, each wheel being freely rotatable on a pin 15 carried on the free end of corresponding levers 16. Levers 16 in cross section are U-shaped in structure and freely fulcrumed upon a common shaft 17, mounted within the side frame structure 18 and extending transversely of the columns of perforations 13.

To electrically insulate the respective levers 16 from the support shaft 17 the hubs 19 of said levers are each made of a dielectric material.

Fast to the underside of support plate 12 is a frame member 20 which has secured thereto by means of screw stud 21 a block 22 constructed of dielectric material. Block 22 extends transversely beneath the contact wheels 14 and has mounted therein a contact bar 23 extending across all of the contact wheels, said contact bar being connected through means of service lead 24 to any suitable source of electrical supply.

Levers 16 are biased each in clockwise direction (Fig. 1) by a related spring 25 connected at one end to the corresponding lever 16 and at their opposite end to a rod 26. So that levers 16 may remain electrically insulated springs 25 are separated from shaft 26 by means of a suitable insulating sleeve 27. Each of the contact wheels 14 therefore is held by its lever 16 with a pair of teeth in engagement with insulating block 22 in such manner that a tooth is spaced adjacent one to each side of contact bar 23 and being normally out of engagement therewith.

Extending transversely within the side framing 18 are insulating strip members 28 within which is secured one end of a plurality of spring leaf circuit members 29, each being electrically insulated from the other. The free end of each of the circuit members 29 rides upon a shoulder or hub portion 30 of the corresponding contact wheel 14 to form electrical connection therewith.

As a card 11 is propelled by the rollers 10 the forward edge of the card will engage the near tooth of contact wheels 14 and will rotate said wheels in unison in a counterclockwise direction. During such operation the

said tooth of all of the wheels 14 are rotated in a wiping action across the contact bar 23 and electrical circuit is extended therefrom to each of the contact wheels 14 and thence to the related spring leaf member 29. As the card continues to advance a succeeding tooth of any of the wheels 14 engaging an unperforated portion of the card will act to prevent further rotation of the related wheel, so that such wheels 14 are lifted upon the card and out of engagement with contact bar 23. Thus during further continued movement of the card any imperforate portions in a card column are adapted to slide along the pair of adjacent teeth of the related column contact wheel and no engagement of the related contact wheel 14 is effected during such portions of a card movement. Where however during such movement of a card a series of perforations 13 traverses a contact wheel 14 the following operation will occur.

As a perforation 13 of the card moves under the near tooth of the related column sensing gear wheel 14 spring 25 of the related lever 16 will act to restore said lever downwardly and cause the wheel to turn, with said tooth entering the perforation 13. As the card continues to advance, the trailing edge of the perforation as it traverses the entered tooth acts to effect a further rotation to the wheel 14 and said tooth is caused to be rotated in a wiping action across the contact bar 23, as shown in Fig. 4. Thereafter the closely spaced perforations 13 act to rotate the contact wheel 14 and cause wiping engagement of successive teeth of said wheel with the contact bar 23, effecting thereby a series of electrical impulses to the related circuit spring leaf member 29. Such operation of a wheel 14 will continue until an unperforated portion of the card again intercepts a rotation of the gear wheel whereupon the trailing edge of the final hole of the series of perforations will act to cam the related wheel 14 out of engagement with the contact bar 23 to rest upon the top surface of the card 11, as shown in Fig. 3. As a record card 11 completely traverses the sensing contact wheels 14 the trailing edge of the card will release gear wheels 14 for a downward movement of levers 16 under influence of their springs 25, so that, said wheels are again positioned upon the insulation block 22, as shown in Fig. 2.

The electrical impulses completed by the engagement of contact wheels 14 as in accordance with a selective series of the perforations upon the record card 11 are adapted to energizing well-known devices such as printing or accumulating magnets in accordance with the particular type of accounting or statistical machine to which the invention may be applied.

While there has been shown and described the fundamental novel features of the invention as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

I claim:

1. A rotary contact device for sensing perforated record cards comprising a card sensing gear wheel having a plurality of teeth for sensing perforations in a record card and wherein said gear wheel includes a plurality of electrical contact areas and each area being in common with a related one of said teeth, an electrical contact member yieldably engageable by successive ones of said contact areas during a rotation of said gear wheel, and wherein said gear wheel is rotatable by the record card through engagement of said teeth with said perforations.

2. A rotary contact device for sensing perforated record cards comprising in combination a card sensing gear wheel having teeth forming a plurality of spaced electrical contact elements, yieldable support means therefor, a fixed electrical contact member adapted for en-

gagement by successive ones of said contact elements during a rotation of said gear, and wherein said gear wheel is rotatable by the record card through engagement of said contact teeth with spaced perforations along the record card for effecting a series of electrical impulses in accordance with said spaced perforations.

3. A rotary contact device for sensing perforations along a record card and effecting a series of electrical impulses in accordance therewith comprising the combination of a freely rotatable gear wheel having a plurality of teeth each including an electrical contact area, a yieldable support member for said gear wheel, means biasing said gear wheel in a direction of the record card, means for advancing a record card, a fixed electrical contact member beneath the plane of movement of said card, and wherein said gear wheel is rotatable by the record card upon engagement of a perforation with a tooth of said gear wheel to effect a wiping engagement of the said contact area thereof with said fixed contact member.

4. A card operated sensing device adapted to effect a series of electrical impulses in accordance with an intermittently spaced series of perforations along a record card, and comprising in combination a gear wheel having teeth for sensing said perforations, and wherein the card sensing teeth serve as electrical contact elements, yieldable support means for said gear wheel, means for moving a record card past said gear wheel, resilient means acting to urge said gear wheel into engagement with the record card so that a pair of adjacent teeth of said gear wheel effect sliding contact along an imperforate face of said card, a fixed electrical contact spaced from the reverse face of said card, and wherein movement of a perforation past said teeth will cause one of said teeth to rock into said perforation, and wherein continued movement of the record card will rotate said gear wheel and bring the teeth thereof successively into wiping electrical engagement with said fixed electrical contact member.

5. Card operated rotary contact devices including means for sensing a perforated record card and comprising in combination a lever having a pivot, a gear freely rotatable on the lever at a point remote from said pivot, and wherein the teeth of said gear form a plurality of electrical contact elements, a resilient electrical contact member acting on said gear to urge the gear into engagement with the record card so that a pair of adjacent teeth of said gear contact the record card, a fixed contact member normally out of engagement with any of said teeth, and wherein movement of a perforation past said teeth will cause one of said pair of teeth to rock into the perforation whereby during a continued movement of said perforation the card will effect rotation of said gear and will cause slideable engagement of said tooth with said fixed contact member.

6. In a card operated rotary contact device having means for sensing perforated record cards moveable past said device the combination comprising a lever having a pivot, a gear rotatable on the lever at a point remote from said pivot, and wherein the teeth of said gear form a plurality of electrical contact members, a hub portion for said gear electrically in common with all the said teeth, a fixed contact member adapted for engagement by any of said teeth, a support member for said fixed contact member constructed of dielectric material, a resilient electrical contact member acting on said hub and urging the gear into engagement with said support member, and wherein a pair of adjacent teeth of said gear contact said support one to each side of said fixed contact.

7. Card operated rotary contact devices including means for sensing perforated record cards moveable past said devices and comprising the combination of a lever having a pivot, a gear rotatable on the lever at a point remote from said pivot, and wherein the teeth of said gear form a plurality of equally angularly spaced elec-

trical contact members, a hub portion on said gear electrically in common with all the said teeth, a fixed contact member adapted for successive engagement of said teeth and located relative to said gear on a line passing through the pivotal center thereof and being perpendicular to the direction of movement of said card, a support member for said contact constructed of dielectric material, a resilient electrical contact member engaging said hub, and yieldable means for urging the gear into engagement with said support member whereby a pair of adjacent teeth of said gear contact the said support member one to each side of said fixed contact.

8. In a card operated sensing device the combination of means for effecting electrical impulses in accordance with columns of perforations spaced along the record cards and comprising a plurality of levers fulcrumed upon a common support shaft and being electrically insulated thereof, a freely rotatable gear wheel mounted upon each of said levers at a point remote from said shaft, and wherein the teeth of each of said wheels sense related columns of card perforations, and wherein said

sensing teeth comprise each an electrical contact element, a dielectric support member, resilient means biasing each of said levers whereby pairs of teeth of said gear wheels are held in yieldable engagement with said support member and wherein each of said resilient means is electrically insulated of the other, a fixed contact bar in common with all the said gear wheels and being mounted within said support member spaced intermediate of said pairs of teeth, resilient electrical contact members insulated each of the other and engageable each with a related of said gear wheels, and means for moving a record card past said gear wheels so that a pair of angularly adjacent teeth of said wheels will effect sliding engagement along the imperforate portion of a record card and wherein said perforations are adapted for effecting rotation of said gear wheels to effect a wiping engagement of successive teeth of said gear wheels with the said contact bar.
